(57) **CLAIM**

The ornamental design for an open air intake, as shown and described.

DESCRIPTION

FIG. 1 is a top, perspective view of the open air intake; FIG. 2 is a right side elevation view of the open air intake, with the left side being a mirror image thereof; FIG. 3 is a front elevation view of the open air intake; FIG. 4 is a rear elevation view of the open air intake; FIG. 5 is a top plan view of the open air intake; FIG. 6 is a bottom plan view of the open air intake; and, FIG. 7 is a perspective view of the open air intake in use. The broken lines shown in FIG. 7 are for the purpose of illustrating environmental matter that forms no part of the claimed design.
